ALBERT SCHMIDT, OF FLINT, MICHIGAN, ASSIGNOR TO CHAMPION IGNITION COMPANY,
OF FLINT, MICHIGAN, A CORPORATION OF MICHIGAN.

METHOD OF FORMING SPARK-PLUGS.

1,234,395.

Specification of Letters Patent.

Patented July 24, 1917.

Application filed January 18, 1917. Serial No. 143,147.

To all whom it may concern:

Be it known that I, ALBERT SCHMIDT, a citizen of the Republic of France, residing at Flint, in the county of Genesee and State 5 of Michigan, have invented certain new and useful Improvements in Methods of Forming Spark-Plugs, of which the following is a specification, reference being had therein to the accompanying drawings.

10 The invention relates to the manufacture of spark-plugs, and has particular reference to the method of forming a gas-tight seal between the insulator and the electrode or other metallic part of the structure.

15 In the present state of the art great difficulty is experienced in producing a plug which will be free from leakage under all conditions of use, and particularly where used with high-speed engines. This difficulty is chiefly due to a differential expansion 20 in the metallic parts and insulation, so that a plug which is gas-tight at ordinary temperatures will often leak when highly heated. Another difficulty is due to the un-

25 avoidable irregularities in the surface of the insulator upon which the sealing flange is seated, so that where adjustment is made, disturbing the contact, leaks are often formed. As a specific instance, it is common 30 to secure the electrode which passes centrally through the insulator by a threaded nut or cap, which is seated on the insulator and is designed to form a seal as well as a means of adjustment; but when adjustment is made the shifting of the bearing frequently 35 produces leakage.

With the present invention these difficulties are overcome by a method of sealing, in which the metal part is exactly conformed 40 to the surface of the insulator upon which it bears, and further is placed under resilient tension so that it will maintain its seat even where differential expansion takes place.

45 In the drawings:

Figure 1 is a section through a portion of a spark-plug with the electrode in initial engagement with the insulator before the sealing operation;

50 Fig. 2 is a similar view illustrating the method of sealing;

Fig. 3 is a plan view of Fig. 2;

Fig. 4 is a diagram illustrating the manner in which the seal is maintained where 55 expansion takes place.

Fig. 5 is a similar view showing a modified construction.

A is the insulator of a spark-plug. B is the electrode passing through said insulator, which as shown is provided with a threaded portion 60 C engaging a correspondingly-threaded recess D in the insulator. E is a collar on the electrode, providing a shoulder for bearing against the outer end of the insulator. With the construction as thus far 65 described, when the threaded portion C is engaged with the threaded recess D, the collar E may be tightened against the end of the insulator; but it is difficult to form a gas-tight seal on account of the irregularities 70 in the insulator surface. By placing a compressible gasket between the shoulder and the insulator, a seal may be made, but when the plug is heated and the metal expanded leakage will occur. This I avoid by 75 sealing in the following manner:

After the electrode has been secured down to cause the collar E to bear upon the insulator, the periphery of this collar is rolled or otherwise subjected to a pressure for forming a groove F therein. As specifically shown, a series of grooving rolls G are mounted on a suitable instrument (not shown), and caused to rotate about the periphery of the collar, and at the same time to 80 bear inward thereon. Each of these rolls has a periphery of V-shaped cross-section, so that as it is forced into the metal of the collar said metal will be deflected in opposite directions. The inner portion will be 85 pressed against the insulator and fashioned into exact conformity to the surface thereof, while the lateral deflection of the outer portion will place the same under tension. Preferably the mass of the metal on the outer 90 side of the groove is greater than that on the inner side, so that when relieved from the pressure of the rolls it will spring inward, placing the inner portion under further tension. As a result there is not only a perfect 95 initial seal formed between the metal and the insulator, but later when the plug is heated and the metal is expanded, so that there is a tendency to separate from the insulator, the tension under which the metal 100 is placed is sufficient to compensate for this expansion and to maintain the tight joint.

What I claim as my invention is:

1. The method of forming a gas-tight joint between a metallic and a non-metallic 110

- part of a spark-plug, comprising the initial seating of the metallic part on the non-metallic part, and subjecting the metal to pressure for deflecting portions thereof oppositely, one portion being conformed to the surface of the non-metallic part against which it bears, and the other portion being placed under tension for holding the first-mentioned portion against its bearing surface.
10. 2. The method of forming a gas-tight joint between a metallic and a non-metallic part of a spark-plug, comprising the initial seating of the metallic part on the non-metallic part, and peripherally rolling the metallic part to form a groove therein, deflecting the metal on one side of said groove to conform the same to the surface of the non-metallic part against which it bears, and placing the metal upon opposite side of the groove under resilient tension for maintaining the pressure upon said bearing.
15. 3. The method of forming a gas-tight joint between the insulator and electrode of a spark-plug, comprising the initial seating of a collar on the electrode against the insulator, and the peripheral grooving of said
20. 25.

collar to deflect the metal oppositely, the metal on the side of the groove adjacent to the side of the insulator being compressed into exact conformity to the surface against which it bears and the metal on the opposite side of the groove being placed under resilient tension.

4. In a spark-plug, the combination with the insulator and a metallic part to be secured thereto, of a collar on said metallic part, peripherally grooved to conform the metal on one side of the groove exactly to the surface of the insulator, the metal on the opposite side of the groove being under resilient tension.

5. In a spark-plug, the combination with an insulator, of an electrode having a threaded engagement with said insulator, and a collar seated upon the end of the insulator, said collar being peripherally grooved, the metal on one side of the groove being conformed to the surface of the insulator and the metal on the opposite side of the groove being under resilient tension.

In testimony whereof I affix my signature.

ALBERT SCHMIDT.
